SECTIONAL BOX AND PLATFORM

Application filed November 10, 1928. Serial No. 318,371.

This invention relates to improvements in sectional box and platform, and more especially to means for stacking box sections on the platform, and one on the other, to hold the same in proper alignment.

Our improved device can be made strong and durable at relatively low cost and with economy in the use of material.

Other features and advantages of our invention will appear more fully as we proceed with our application.

In that form of device embodying the features of our invention shown in the accompanying drawing, Figure 1 is a view in side elevation of a platform with two box sections stacked thereon; Fig. 2 is a top plan view, Fig. 3 is a view in end elevation, and Fig. 4 is a view taken as indicated by line 4 of Fig. 3.

As shown in the drawings, 10 indicates in general a raised platform preferably made out of pressed steel. In the forming of the platform a substantially rectangular sheet of metal is used, and the side margins bent downwardly to form vertical side walls as indicated by 10^a. The top of the platform is indicated by 10^b. In order to strengthen the platform, the vertical side walls are provided with vertical corrugations 10^c, said corrugations preferably having their upper ends connected by horizontal corrugations 10^d extending across the top surface of the platform. The corrugations 10^c and 10^d serve to strengthen and stiffen the platform, and the corrugations 10^e also serve to co-operate with the retaining lugs on the lower box section to hold the same in place, as will be more particularly described hereinafter.

A plurality of box sections are adapted to be stacked on the platform in order to form a box or bin of any desired height. These sections are also preferably formed out of pressed steel, each comprising a rectangular frame with four side-walls and open at the top and the bottom, or, if desired, the bottoms may be closed. In Fig. 1, we have shown two of such sections stacked on the platform, each being indicated by 11. In Fig. 3, one of these sections is shown. Each box section preferably has its side walls provided with horizontal corrugations, here

shown as projecting outwardly, as indicated by 11^a. These corrugations serve to strengthen and stiffen the box sections and also assist in holding the retaining lugs in place, as will be described more particularly hereinafter.

We shall now describe the retaining lugs used to hold the lower box section on the platform and the upper box sections on the lower ones. Each box section is provided with two retaining lugs attached to each side-wall, as indicated by 12. Each of these lugs has its upper part provided with two or more corrugations 12^a, 12^b, fitting nicely over one or more of the lower corrugations 11^a, 11^b, of the box section, and the lug is held in place by two rivets 13, 13. By this construction, the lug may be very securely and firmly held in place by the use of only two rivets. The corrugations on the lug fit over and rest snugly against the corrugations in the box section, thus resisting any lateral twisting of the lug. Each side lug has a lower depending end, as indicated by 12^b, which is adapted for insertion in one of the vertical corrugations 10^c in the side wall of the platform. By inserting the lug ends in these vertical corrugations, the top of the platform does not need to be slotted to accommodate them; and this permits the box sections to be substantially as long and wide as the platforms, thus increasing the capacity of the box over those formerly used.

Each box section is also provided with a retaining lug 14 at each end, these lugs being similar to the side lugs 12. Preferably, however, the upper parts of these lugs are made somewhat longer and provided with four corrugations 14^a fitting over the corrugations 11^a in the end wall of the box section. We have here shown these end lugs as fastened to the box sections with three rivets 15. The lower depending end 14^b of each end retaining lug is adapted to fit over the end of the platform to assist in holding the lowermost box section in place on the platform.

Our box section may also be fitted over a lower box section, as shown in Fig. 1, in which case the depending ends 12^b of the side

lugs and the depending ends 14^b of the end lugs fit over the box section underneath.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as possible in view of the prior art.

What we claim as new, and desire to secure by Letters Patent, is:

15 A box having vertical side walls and a removable bottom, said bottom carrying vertical flanges adapted to space the same from a support, said flanges having vertical corrugations therein, and said side walls having 20 depending members adapted to engage the corrugations in the flanges of the bottom to prevent relative horizontal movement between the side walls and the bottom.

In witness whereof, we have hereunto set 25 our hands this 7th day of November, 1928.

CARL L. CLARK.

WILLIAM W. GALBREATH.
